FERNANDO ALONSO, OF LUCHANA-BARACALDO, SPAIN, ASSIGNOR TO THE WEAVING MACHINES COMPANY LIMITED, OF LONDON, ENGLAND

ROTARY LOOM FOR THE MANUFACTURE OF TEXTILES OF ALL KINDS IN THE FORM OF A TUBE

Application filed November 29, 1929, Serial No. 410,335, and in Spain December 5, 1928.

This invention relates to circular looms and has for an object to provide an improved loom of this type which shall be very simple and inexpensive both in manufacture and 5 operation, and in which the number of independently operable parts is reduced to a minimum.

In the design of circular looms difficulty has almost invariably been experienced in 10 providing satisfactory means for impelling the shuttles around their continuous circular path and also especially in the production of webs of large circumference, in connection with the "beating-up" of the weft 15 threads deposited in the warp shed by the shuttles; the problem of devising means for forming the shed and of obtaining even tension of the warp threads as the shed is formed and reformed has been comparative- 20 ly easy.

In one known type of circular loom the shed extends in a plane intersected at right angles by what may be termed the "weaving axis", which latter is vertical, whilst a plurality of slides, one for each warp thread, are mounted in guides disposed in a circle around the weaving axis; longitudinal reciprocatory motion in a direction parallel with said axis being imparted to the slides 25 by means of a cylindrical grooved cam. In this type of loom each warp thread passes through an eye attached directly or indirectly to the corresponding slide a projection on which is adapted to bear against an inclined 30 surface of the shuttle; motion being imparted to the slides in such manner that as those at one end of the shuttle are moving towards one another and thus closing the shed at that 35 end of the shuttle, thus causing the projection to bear on the latter to impel it forward, those at the other end of the shuttle are moving apart from one another, thus opening the shed and permitting the shuttle to move 40 forwardly; whilst the shuttle itself is mounted upon a carrier which is shaped at one side so as to engage in undercut recesses formed in the guides for the shuttle-impelling slides, between which the warp threads extend and 45 pass as the shed is formed and reformed. It 50 will be observed that the shuttle thus travels

around what may be termed the inner periphery of a circular track constituted by the guides upon the shuttle-impelling slides, and these latter serve also for opening and closing the warp shed. Such an arrangement 55 has been proposed for the production of webs of comparatively small circumference, such as hoses and for covering cores of metal or other material with woven sheets. In view of the disposition of the shed with regard to 60 the weaving axis, there is little or no need for any special means to be provided for beating-up purposes.

In one loom of this general type it has been proposed to form lateral extensions of the 65 shuttle-impelling slides with notches in which the shuttle carrier is adapted to slide so that said shuttle-impelling slides constitute in themselves a track for the shuttle. In this case it was also proposed to extend the upper 70 end of each slide towards that end of the shed at which the weft thread is deposited by the shuttle, such extensions being formed themselves with inclined surfaces adapted to bear against the weft threads and beat them 75 up in the desired manner. In connection with this loom it was suggested that in order to assist in guiding the shuttle a series of thin upstanding divisions might be formed immediately above the guides for the shuttle- 80 impelling slides and that in each division a part-circular or other shaped groove should be cut in circular alignment with the notches in said slides for the shuttle carrier; the arrangement being such that the shuttle will 85 travel along the aligned slots in said divisions.

For the production of webs of large circumference it has, as a rule, been found desirable that the weft shed should be formed parallel with the vertical axis of weaving, or, in other words, should lie substantially in a cylindrical surface co-axially of the weaving axis. In such an arrangement it is necessary that some provision should be made for beating-up the weft threads, and one proposal to this end was that the shuttle should be supported in part at least by one or more thin double conical wheels which would bear upon the weft threads as they are deposited, the 95 100

weaving taking place in such a case in a downward direction.

It has also been suggested that the shuttle should be impelled around a circular path by magnetic means, and, further, that in cases where the weaving takes place in an upward direction, the beating-up should be effected by a plurality of radially disposed levers, one between each pair of adjacent warp threads, and which are rocked about horizontal pivots by means of a circular grooved cam.

As a further development of this type of circular looms, it has been proposed that the warp threads should extend through a circular reed-like member mounted for motion after the manner of a swash plate, the shuttle resting upon the cross pieces of the reed which extend between adjacent warp threads and being impelled throughout the circular path by the swash plate motion of the reed, which latter serves at a point diametrically opposite that of the shuttle at any time being to beat-up the weft thread deposited by the shuttle. Further, as a development of this and the previous arrangements, it has been proposed that a series of radial levers, each extending between an adjacent pair of warp threads, should be fulcrumed about horizontal axes outside the shed and extend at their inner ends into the groove of a circular grooved cam mounted for rotation about the weaving axis within the warp shed, the shuttle resting upon these levers between the two "walls" of the warp shed, and motion being imparted to the levers by the cam in such manner that they serve not only to impel the shuttle around its path, but also to beat-up the weft thread deposited thereby.

In yet another arrangement a similar series of radial levers has been provided mounted about horizontal pivots inside the warp shed and extending each through its pivotal axis outwardly between adjacent warp threads and inwardly to engage at its ends with a circular groove cam. In both these arrangements the shuttle impelling and beating-up levers themselves constitute the shuttle track; independent means are provided for forming the shed, and both are subject to the disadvantage that during its motion around the circular path, the shuttle will inevitably especially if at all high speeds are employed, bear laterally against the threads of the warp shed, with the consequent risk of damage to the latter.

In a circular loom according to the present invention, however, the warp threads pass, in a direction substantially parallel with or inclined at a comparatively small angle, preferably less than 45° to the central axis of weaving, through a stationary reed-like annular frame, each radial cross member of which is formed with an undercut transverse recess in which a shuttle carrier is adapted

to engage so as to be restrained positively to travel in a path determined by said recessed cross members, and a plurality of levers, pivoted intermediately of their lengths about horizontal axes, extend each radially inwards from its pivot to engage in the groove of a cylindrical grooved cam concentric with the weaving axis, and radially outwards from its pivot to pass, as it is rocked about said pivot by the action of said cam, through the warp shed and to bear first at points remote from said pivot against a shuttle and/or its carrier to impel the shuttle, and bear subsequently at points nearer said pivot, against the weft thread deposited by the shuttle to beat-up said thread.

A circular loom according to the invention is illustrated by way of example in the accompanying diagrammatic drawings, of which:

Figures 1 and 2 show the complete loom in side elevation;

Figure 3 is a diagram showing in plan the form of the warp shed and the corresponding position of the two shuttles employed;

Figure 4 is a part sectional fragmentary view showing in elevation the shuttle track and associated parts;

Figure 5 shows in front and side elevation the construction of the shuttle-impelling and beating-up levers;

Figure 6 is a part sectional fragmentary schematic view showing in development the shuttle track and associated parts;

Figure 7 is a fragmentary diagram showing in plan and elevation means whereby the warp threads are maintained in tensions as the shed is formed and reformed;

Figure 8 is a diagram corresponding with Figure 3, showing in plan the formation of warp sheds and the disposition of the shuttles in the case where four shuttles are employed; whilst

Figure 9 is a cross sectional view on the line A—B of Figure 6.

As shown, the machine is mounted upon a bed plate 0 to which frame members 1, thereof are bolted. At the centre of the bed plate 0 there is supported the lower end of a vertical fixed shaft 2, on which is rotatable a hollow shaft 3, from which motion is imparted to the moving parts of the loom. This shaft 3 has fast thereon a hand-wheel 4 whereby the machine can be operated by hand, as is sometimes desirable. Above the handwheel 4 on the shaft 3 is fast an ellipsoidal eccentric 5 which serves to operate the means for maintaining constant the tension of the warp threads as the shed is formed and reformed. These means comprise a flexible hoop or ring 7 connected with the eccentric 5 by tie rods 9 attached at their inner ends to an endless chain forming a collar or strap around the eccentric 5 (see Figure 7 of the drawings), the hoop 7 co-operating with the warp 130

threads in conjunction with a rigid hoop or ring immediately thereabove.

Two eccentrics 10 are fast upon the shaft 3 above the ellipsoidal eccentric 5 in such positions that their throws are diametrically opposed and serve together to operate the heddle mechanism for forming and reforming the warp shed (see Figure 3 of the drawings). Each of these eccentrics is fitted with 10 a non-rotary collar or strap, and in the case illustrated for each pair of adjacent warp threads a heddle member, indicated at 12 (see Figure 3 of the drawings), is attached at one end to one of the eccentrics 10 and passes 15 radially outwards around a small roller 11, and then inwardly to be attached at its other end to the other eccentric 10, the corresponding warp threads passing through the eyes 12, as shown clearly in Figures 2 and 3 of the 20 drawings. Thus, as the eccentrics 10 rotate with the shaft 3, the upper and lower parts of the heddles move radially inwards and outwards, respectively, twice for every revolution of the shaft 3, so that two sheds are 25 formed which virtually travel around the axis of the machine as the shaft 3 rotates.

In a case where it is desired to use more than two shuttles, the necessary movements of the warp threads can be effected, as shown 30 by way of example in Figure 8, where four shuttles are employed, by modifying the shape of the eccentrics in the manner which is clearly shown in Figure 8 of the drawings. However many shuttles are employed 35 the small rollers 11 over which the heddles pass are mounted so as to be capable of slight radial movement; in the case illustrated they are mounted on a flexible hoop. This is necessary because, as will be observed, the radial distance between the axis of the machine and any one of these rollers 40 11 varies with the position of the eccentrics. In both Figures 3 and 8 of the drawings a small number only of heddles is illustrated 45 for the sake of clearness. It should be borne in mind, however, that the number of heddles must equal half the number of warp threads.

Fast upon the shaft 3 near the upper end thereof is a cylindrical grooved cam 13, into 50 the groove 14 of which fit the heads or inner ends of levers 15 (see Figures 1, 2, 4 and 5) to which latter the cam 13 imparts oscillatory movement, as shown particularly in Figure 4. Each of these levers is fulcrumed 55 about a horizontal axis from which it extends in a direction radially of the shafts 2 and 3.

The upper end of the fixed shaft 2 extends 60 above the upper end of the rotary shaft 3 and carries a plate or disc 17 upon which the pivots of the levers 15 are mounted (see Figures 1, 2 and 4). Also mounted upon the upper end of the shaft 2 are a rigid hoop or ring 18 (see Figures 1, 2 and 4) which serves to control 65 the circumferential dimensions of the

woven fabric, and a looped rod 19 which serves to guide the fabric on its way to a beam upon which the fabric is wound. In the case illustrated two warp beams 20 (see Figures 1 and 2) are carried at the lower 70 parts of the side frame members 1.

Motion is imparted to the rotary shaft 3 from pulleys 21 (see Figure 2) on the shaft 22 connected operatively with the shaft 3 by bevel gearing 23, 24; the beam on to which the 75 woven fabric is wound is supported independently of the machine, and the necessary rotation is imparted thereto through worm gear 25, a vertical shaft 26 and a gear box 27, which latter may be adjusted as required to govern 80 the closeness of the warp threads in the woven fabric.

An annular track 8 for the shuttles is carried by the side frame members 1 and is of reed-like formation, and into the openings 16 85 thereof the end portions of the levers 15 lie when said levers 15 occupy their lowermost positions. The cross members of this reed-like shuttle track are formed with undercut transverse recesses (see Figures 4, 6 and 9) 90 in which a shuttle carrier fits and is freely slideable.

The shuttle carrier 6 (see particularly Figure 6) is inclined upwardly from and laterally of the track at both ends. 95

From a consideration of Figures 4 and 6, it will be observed that as the levers 15 are raised about their pivots, they will bear against the inclined surfaces at the rear of the shuttle carrier so as to drive it along the 100 shuttle track, the levers immediately in front of the shuttle moving simultaneously downwards to limit the motion thereof. The downwardly moving levers 15 in front of the shuttle prevent it travelling too far as, for 105 example, under its own momentum.

It will be observed that each shuttle is moved around the circular track in time with the virtual motion of the corresponding warp shed around the axis of the machine, the 110 warp threads being maintained in even tension as the shed advances by means of the appropriately timed action of the ellipsoidal eccentric 5 and flexible hoop or ring 7.

The shuttles proper are secured to their 115 carriers by any known or convenient means, and each lever 15 serves not only for impelling the shuttles, but also as a reed. In the case illustrated, a plurality of warp threads pass through each space 16 of the shuttle track and each lever 15 is formed as a reed having a corresponding number of openings through which the warp threads pass.

As will be clearly seen from Figures 4, 5 and 6 of the drawings, the levers 15 serve, 125 firstly, to impel the shuttle, and then, towards and at the end of their upward movement, to beat-up the warp thread deposited thereby.

A loom according to the present invention 130 possesses the advantages that the shuttles are

- to all intents and purposes positively driven at all times, that the beating-up operation is progressive and takes place continuously as the weft threads are deposited, and that the shuttle is constrained to move in a predetermined path in such manner that it cannot possibly foul the warp threads. The diameter or circumference of the woven fabric produced will depend upon the diameter of the ring 18 carried at the upper end of the fixed shaft 2, and by varying the dimensions of this ring, or by using rings of various diameters, woven fabric or webs of varying dimensions can be produced by a single loom.
- Having now particularly described and ascertained the nature of my invention and in what manner the same is to be performed I declare that what I claim is:
1. A circular loom in which the warp threads pass in a direction substantially parallel with or inclined at a comparatively small angle less than 45° to the central axis of weaving, comprising a substantially reed like annular frame, a plurality of radial cross members therein, each of said cross members having an undercut transverse recess, a shuttle carrier engaging and positively restrained to travel in a path determined by said recessed cross members, a shuttle, a cylindrical grooved cam concentric with a weaving axis, and a plurality of levers pivoted intermediate of their lengths about horizontal axes, said levers extending radially inward from their pivot to engage in the groove of said cam and extending radially outward to pass during movement by said cam through the warp shed and to bear first the points remote from said pivot against said shuttle and/or its carrier to impel the shuttle and to subsequently bear at points nearer said pivot against the weft thread deposited by the shuttle to beat up said thread.
  2. A circular loom as claimed in claim 1 wherein the pivotal axis of the shuttle impelling and beating up levers are deposited at a distance from the weaving axis less than the inner radius of the annular reed like frame and spaced from the latter axially thereof, each lever being adapted to be rocked by the cam from a position in which the outwardly extending arm thereof extends from the pivot to the inner end of the space between adjacent cross members of the annular reed like frame to a position in which said outwardly extending arm extends through the warp shed and bears at a point intermediate of its length against a weft thread deposited by the shuttle.
  3. A circular loom as claimed in claim 1 wherein the cross members of the annular reed like frame are so spaced from one another that a plurality of warp threads pass between adjacent cross members, the outer arm of each of the levers being of substantially L shaped formation and being formed as a section of a reed, the base of the L being adapted to lie between adjacent cross members of the annular reed like frame when the lever is in one extreme position, to space the corresponding warp threads from one another, and the other limb of the L being adapted to bear near its junction with the base against an inclined surface formed on a shuttle carrier and/or its shuttle to impel the latter, and when in its other extreme position to bear at a point nearer its pivot against the weft thread deposited by the shuttle and thus to pivot up said thread.
4. A circular loom having an annular reed like frame constituting a shuttle track and shuttle impelling beating up levers and a cylindrical grooved cam, the axis of which is coincident with the axis of weaving, a plurality of eccentrics mounted thereon, a plurality of healds or heddle frames extending radially beneath the reed like annular frame operated by said eccentrics, and means to maintain the tension of the warp threads substantially constant at the shed is formed and reformed.
- In testimony whereof I affix my signature.
- FERNANDO ALONSO.
